2 SHEETS—SHEET 2.

UNITED STATES PATENT OFFICE.

EDWIN LUNDGREN, OF PITTSBURGH, PENNSYLVANIA, ASSIGNOR TO WESTINGHOUSE ELECTRIC & MANUFACTURING COMPANY, A CORPORATION OF PENNSYLVANIA.

REFUSE-DISCHARGE MECHANISM FOR FURNACES.

1,355,487.

Specification of Letters Patent. Patented Oct. 12, 1920.

Application filed October 14, 1918. Serial No. 258,059.

To all whom it may concern:

Be it known that I, EDWIN LUNDGREN, a citizen of the United States, and a resident of Pittsburgh, in the county of Allegheny and State of Pennsylvania, have made a new and useful Invention in Refuse-Discharge Mechanism for Furnaces, of which the following is a specification.

This invention relates to refuse discharge mechanisms for furnaces or stokers.

An object of the invention is to produce a refuse discharge mechanism for stokers in which means are employed for insuring complete combustion of the fuel prior to its discharge into the ash pit.

A further object is to produce a refuse crushing and discharging device for stokers in which adjustable means are employed for controlling the crushing operation and for relieving the crushing device of excessive strains.

These and other objects, which will be made more apparent throughout the further description, are attained by means of apparatus embodying the features herein described and illustrated in the drawings accompanying and forming a part hereof.

In the drawings: Figure 1 is a diagrammatic sectional view of an underfeed stoker equipped with apparatus embodying my invention.

Fig. 2 is a fragmental sectional view on an enlarged scale of a portion of the refuse discharge mechanism disclosed in Fig. 1.

Fig. 3 illustrates an embodiment of my invention as employed in connection with a double ended stoker.

In my copending application filed Feb. 9, 1918, and serially numbered 216,389, I have illustrated a refuse discharge mechanism specially adapted for use in connection with underfeed stokers. The present invention is a modification or improvement of the mechanism there disclosed, and while it is primarily adapted for use in connection with underfeed stokers, it may, with slight modifications, be employed in connection with furnaces of other types.

The stoker illustrated in Fig. 1 consists of alternately arranged retorts 5 and air delivering fuel supporting surfaces 6. Fuel is fed into the forward end of each retort from a hopper 7 and by means of a plunger 8. The plunger is driven by any suitable motor or engine 8' through the medium of

the connecting rod 21' and the period of its reciprocations may be varied to correspond to the desired rate of fuel feed. The fuel fed into each retort is forced outwardly across the fuel supporting surfaces 6 and 60 is also moved downwardly across the surface and through the retorts toward the refuse discharge mechanism 9. As illustrated, the refuse discharge mechanism consists of a receptacle formed at the rear end 65 of the furnace and between the furnace and the bridge wall. The forward wall of the receptacle consists of an oscillating grate section 10, a stationary grate section 11, and an adjustable apron 12. The rear wall of 70 the receptacle consists of a stationary grate section 13 and an adjustable apron 14. The aprons 12 and 14 are located on opposite sides of a crushing and discharging roll 15 which, in effect, forms the bottom of the 75 receptacle.

In Fig. 2, I have illustrated the grate section 10 in detail and, as shown, it includes a frame 16 which is fulcrumed at 17 on a bracket mounted on a stationary portion of 80 the furnace structure. A series of overlapping grate bars 18 are mounted on the frame 16 and are held in place by means of a locking bar 19 which is bolted or otherwise secured to the frame. As shown, the locking bar is provided with an upwardly extending lug 20 which engages a downwardly projecting foot 21 formed on the next adjacent grate bar and which prevents the grate bar from moving relatively to 85 the locking bar. A similar lock is provided between each grate bar and the grate bar located immediately above it. The frame 16 is oscillated around the trunnion 17 by means of the stoker driving mechanism. As illustrated, the oscillating mechanism consists of the connecting rod 21' pivoted to a crank arm 21'' which is rotated by the motor 8', a link 22, a lever 23, and a link 24. The lever 23 is pivotally mounted on a bracket 25 secured to the stationary portion of the stoker frame and the link 24 is pivotally connected to both the lever 23 and a bracket 26 formed on the lower end of the frame 16. With this arrangement the grate 100 section 10 swings upwardly and in a direction substantially across the mouth of the receptacle; the motion of the grate section is however relatively small as compared to the width of the receptacle and is merely 105 110

adapted to break up refuse material discharged into the receptacle and to prevent bridging across the mouth of the receptacle. As shown, the stationary air delivering section 11 is located immediately below the section 10 and forms with that section the rear face of an air box 27 which receives air through a port 28 from an air supply passage 29 forming a part of the blast delivery system of the furnace. As shown, the passage 29 is provided with a damper controlled inlet port 30. The structure just described is omitted from Fig. 1, but is clearly illustrated in Fig. 2.

15 The apron 12 is pivoted near its upper edge on a trunnion 31 which is supported in suitable brackets mounted on the frame of the stoker. The upper edge of the apron is located adjacent to the lower edge of the 20 grate section 11, and the lower edge of apron is adapted to be moved toward and away from the roll 15. The apron 14 is similar in some respects to the apron 11 and is pivotally mounted at its upper end on a trunnion 32 which is in turn mounted on a stationary bracket 33. The lower edge of this apron is also capable of being moved toward and away from the roll 15. As shown, the two aprons 12 and 14 may be simultaneously 25 adjusted from the front of the stoker by means of a hand wheel 34. In the drawing the stem of the hand wheel is provided with a worm gear 36 which meshes with a rack 37 pivotally mounted on a trunnion 38. 30 This rack is operatively connected to a lever 39 by means of a link 40. The lever is fulcrumed at an intermediate point and one end is connected to the apron 12 by a link 41, whereas the other end is connected to the 35 apron 14 by link 42, and a lever 43. With this arrangement a movement of the rack 37 in one direction will move both aprons outwardly away from the roll, whereas a movement of the rack in the opposite direction 40 will move them toward the roll.

In order to prevent injury of the aprons or of the roll 15 in case the roll is incapable of crushing refuse material fed to it from the receptacle the aprons are yieldingly held 50 in the adjusted positions by means of a spring 44 which forms a part of the link 40. As shown, the link is formed in two parts, one part including a housing for the spring 44 and the other part consisting of a rod 55 which is operatively secured to the spring housing by means of the spring. The arrangement is such that pressure on either apron tending to force it outwardly will compress the spring and thereby permit the 60 apron to move away from the roll without subjecting either the roll or the apron to undue strains.

The roll 15 may be of the usual construction and the operating mechanism may be 65 similar to that described in my before men-

tioned application. The grate section 13 may be provided with air discharge apertures 45 for delivering air under pressure to the material passing downwardly through the receptacle. The grate bars 18 of the 70 section 10 are preferably provided with air passages 46 for delivering air under pressure to the material entering the mouth of the receptacle and the grate section 11 is also provided with air passages 47. With 75 this arrangement fuel entering the receptacle is provided with air under pressure and, in addition to this, the amount of air delivered may be controlled by the damper 49 controlling the port 30. 80

In Fig. 3, I have illustrated diagrammatically an arrangement of my invention in connection with two stokers located end to end. As illustrated, a refuse receptacle 50 is provided between the two stokers. Two 85 clinker grinding rolls 51 are provided at the bottom of the receptacle for crushing and discharging refuse contained in the receptacle. An apron 12' is located on each side of the rolls 51, and each apron may be 90 individually controlled from the front of its corresponding stoker, although a connection such as described in connection with Fig. 1 may be employed for simultaneously adjusting the position of both aprons. Each furnace of Fig. 3 is shown provided with an oscillating grate section 10' and a stationary grate section 11', all of which sections are adapted to deliver blast to the upper 95 portion of the receptacle 50. It will, of course, be understood that a spring connection such as the spring 44 may be employed between each apron 12' and its adjusting means.

While I have in effect described but two 100 embodiments of my invention, it will be apparent that various changes, modifications and substitutions may be made in the apparatus illustrated as embodiments of the invention without departing from the spirit 105 and scope of the same.

What I claim is:

1. In combination with a stoker, a refuse discharge mechanism comprising a movable air delivering section over which fuel discharged from the fuel supporting section of the furnace passes, a receptacle located below said section and into which refuse and fuel are moved by the movements of said section, including a refuse crushing and 115 discharging device forming a bottom for said receptacle, and adjustable aprons located on each side of said crushing and discharging device and means for yieldingly holding said aprons in adjusted positions 120 whereby the opening movement of one apron actuates the opposite apron.

2. In combination with a stoker, a refuse crushing and discharging device, a receptacle above said device into which refuse 130

from the fuel supporting sections of the stoker is fed, including movable aprons located on opposite sides of said device and forming front and rear walls of said receptacle, means actuated from the front of the furnace for adjusting the position of said aprons with respect to the device, and yielding means for holding said aprons in adjusted positions whereby the opening movement of one apron actuates the opposite apron.

10 3. In combination with a stoker, a refuse crushing and discharging device, a receptacle located above said device and into which refuse from the fuel supporting portion of the stoker is fed, including movable aprons located on each side of said device and forming front and rear walls of said receptacle, means actuated from the front of the furnace for simultaneously adjusting the positions of said aprons, and means for yieldingly holding said aprons in adjusted position.

20 4. In combination with a stoker, a receptacle into which refuse from the fuel supporting portion of the stoker is fed, including a refuse crushing and discharging device forming the bottom of the said receptacle and aprons located on opposite sides of said device and forming front and rear walls of said receptacle, means located at the

front of the furnace for simultaneously adjusting the positions of said aprons, connections between said means and said aprons and a spring included in said connections 35 for yieldingly holding said aprons in adjusted positions.

5. In combination with a stoker, a refuse discharge mechanism comprising a receptacle located at the rear of the fuel supporting portion of the stoker, including a fuel crushing and discharging roll forming the bottom of said receptacle, and movable aprons located on opposite sides of said roll and forming parts of the front and rear 45 walls of said receptacle, an oscillating air delivering fuel supporting section over which refuse from the fuel supporting portion of the furnace is fed into said receptacle, means driven by the driving mechanism of the stoker for periodically oscillating said section, means located at the front of the furnace for adjusting the positions of said aprons and connections between said means and said aprons for yieldingly holding said aprons in the adjusted positions. 50

In testimony whereof, I have hereunto subscribed my name this 8th day of October, 1918.

EDWIN LUNDGREN.
